UNITED STATES PATENT OFFICE.

WILLIAM HUNTER AND MAY GILL, OF BLACKPOOL, ENGLAND.

SILENCER FOR INTERNAL-COMBUSTION ENGINES.

Application filed January 5, 1923, Serial No. 610,845, and in Great Britain September 30, 1922.

This invention relates to improvements in silencers for internal combustion engines.

The object of the present invention is to provide a silencer which is efficient in operation and provides no back pressure to the exhaust of the engine and at the same time is simple to manufacture.

In the drawings which show one embodiment of the present invention:—

10 Fig. 1 is a view in longitudinal section of the device, and

Fig. 2 is a section on the line 2—2 of Fig. 1.

15 The invention is directed broadly to a silencer of the ejector type provided with baffle means.

20 Referring in detail to the drawings the device comprises essentially a cylindrical casing 1 to which are attached by threads 2 or other suitable means, conical end pieces 3 and 4. The end piece 3 is provided with suitable clamping means 5 for attaching the silencer to the exhaust pipe of the engine.

25 Mounted within the cylindrical casing 1 is an ejector tube 6 centrally disposed carrying a continuous spiral baffle 7. Between the inlet end of the ejector tube 6 and the commencement of the spiral baffle is a space 8 forming a stabilizing chamber. Mounted on the inlet end of the ejector tube is a perforated baffle plate 9 the perforations being shown at 10. The diameter of said plate is slightly in excess of the inner diameter of the casing 1 and the plate is held between the inlet end of the casing 1 and a flange 11 formed on the inner face of the end piece 3. In this way the ejector is conveniently mounted within the casing 1.

40 The ejector tube 6 has at its exhaust end a nozzle 12 which is adapted to project within the cone portion of the end piece 4.

45 The spiral baffle 7 is mounted on the upper surface of the ejector tube 6 and the distance between each succeeding convolution is such that the area for the passage of the gases bounded by the spiral baffle 7 and the outer casing 1 is directly or suitably proportioned to the area of the opening of the 50 exhaust valve in view of the time factor involved. The area of entrance to the spiral is never less than the area of the exhaust pipe.

55 The area of the perforations 10 in the baffle plate 9 is greater than the area of the

exhaust pipe. The spiral baffle 7 is extended slightly in a direction substantially parallel to the axis of the ejector tube 6 for a short distance at the beginning and end of said baffle.

60 The continuous spiral baffle 7 is preferably formed of a plurality of annular discs which are split along one radius and the ends drawn out in opposite directions substantially parallel with the axis of the disc. In 65 this way each disc forms one complete convolution. The separate convolutions are riveted or otherwise secured as shown at 13 to form a continuous spiral baffle which is mounted on the ejector tube in any suitable 70 manner such as by brazing at certain points indicated by 14.

75 It will be understood that the size of the aperture of the ejector tube and the size of the passage formed by the baffle may be varied to suit the particular type of engine with which the silencer is to be used.

80 The stabilizing chamber 8 used in combination with a continuous spiral baffle has been found of considerable importance in obtaining an efficient practical result. The function of the stabilizing chamber is to stabilize the exhaust gases which are admitted to the silencer with considerable velocity and to avoid any turbulence which 85 would otherwise be set up and at the same time to allow of an uninterrupted passage of the gas between the spiral baffles. The method of operation of this device is essentially similar to other ejector devices of a 90 similar nature in that the action of the ejector tube causes the gas to be drawn simultaneously into the stabilizing chamber and thence through the spiral passage exterior 95 of the said ejector tube.

We claim as our invention:—

100 A silencer for internal combustion engines comprising in combination, a cylindrical casing, a conical end piece mounted on the rear end of said casing, a conical end piece mounted on the front end of said casing and provided with a shoulder on its inner face, a tube concentric with said cylinder and adapted to form an uninterrupted passage 105 for exhaust gases, an ejector forming a part of said tube, a baffle plate formed integrally with said tube and secured between the front end of said casing and the shoulder of 110 said conical end piece, a continuous uninterrupted spiral baffle plate extending be-

tween the outer surface of said tube and the inner surface of said casing and mounted on said ejector tube to leave a substantial chamber between said baffle plate and the commencement of the spiral baffle in order to form a stabilizing chamber for the prevention of turbulence and means to at-

tach said forward conical member to the exhaust pipe of the engine.

In witness whereof, we have hereunto signed our names this 20 day of December, 1922.

WILLIAM HUNTER.
MAY GILL.
